IGNITION MEANS FOR RADIAL ENGINES

Kenneth A. Harmon, Longmeadow, Mass., assignor to Wico Electric Company, West Springfield, Mass., a corporation of Massachusetts

Application April 18, 1939, Serial No. 268,559

3 Claims. (Cl. 123—55A)

This invention relates to improvements in ignition means for internal combustion engines and, more particularly, to engines of the twin row, radial type, such for example as are often used in aircraft.

With engines of this type it has been the practice heretofore, to use a breaker point mechanism which consists of a single cam having as many lobes as there are cylinders in the engine, and a single breaker arm cooperating with this cam. The reason for this arrangement is that the lobes of the cam are irregularly spaced in order to secure ignition accurately when the pistons are in firing position. Due to the use of a master connecting rod for one cylinder of each series of radial cylinders and the articulation of the other connecting rods of the same series to the master connecting rod instead of directly to the crankshaft, the pistons do not reach firing position in their respective cylinders at equal angular movements of the crankshaft. The unequally spaced lobes of the ignition cam compensate for the aforesaid discrepancy and cause ignition to occur accurately when the pistons are in firing position.

Many difficulties attend the use of an ignition cam of this class in an engine having a large number of cylinders, such as eighteen for example. The cam must be made large in diameter to accommodate so many lobes and it has to be made by special methods which are expensive. Then, in use there is more rapid wear of the breaker points due to the rapidity with which they are moved into and out of engagement. It is desirable to divide the work between two or more breaker arms and, while this might easily be done in other types of engines, it has not been considered feasible in engines of the type aforesaid.

This invention has for its object the provision of a breaker point mechanism for use in a twin row, four cycle internal combustion engine of the radial cylinder type, characterized by a single cam and two cooperating breaker arms which operate alternately and are so located as to engage the cam at angularly spaced points thereon—the spacing being such that accurately timed ignition can be had for each cylinder notwithstanding the irregular spacing of the lobes of the cam.

The invention will best be understood as the detailed description proceeds and the scope of the invention will be pointed out in the appended claims.

The invention will be disclosed with reference to the accompanying drawings, in which:

Fig. 1 is a diagrammatical view of a twin row, radial type of aircraft engine for which the invention is suitable;

Fig. 2 is a fragmentary view taken like Fig. 1 but showing the parts in different relative positions;

Fig. 3 is an enlarged view of a breaker point mechanism embodying the invention;

Fig. 4 is an enlarged view of the cam for actuating the breaker point mechanism; and

Fig. 5 is a diagram illustrative of a conventional form of ignition means of which said mechanism forms a controlling part.

Referring to Fig. 1, there is shown in diagrammatical form a four cycle, eighteen cylinder internal combustion engine, adapted for aircraft. The engine is of the radial type with the cylinders arranged in two rows of nine cylinders each, the cylinders of each row being disposed radially with respect to the crankshaft. The nine cylinders of one row are equidistantly spaced in a circular series and are designated

10 1, 3, 5, 7, 9, 11, 13, 15, and 17. The nine cylinders of the other row are likewise equidistantly spaced in a circular series and are designated

15 2, 4, 6, 8, 10, 12, 14, 16 and 18. The crankshaft, marked 20, has a double crank 21 and the two

20 crankpins, marked 22 and 23, are disposed in diametrically opposed relation. The pistons are

25 shown at 25 and their wrist pins at 26. The connecting rod 27 for the piston of cylinder 13 is a so-called master rod and is rigidly joined

30 to a spider 28 which is rotatably mounted on crankpin 22. The connecting rod 29 for cylinder 8 of the other series is likewise a master rod and is rigidly fixed to a spider 30 which is rotatably

35 mounted on crankpin 23. The other connecting

40 rods 31 of the first series are articulated to spider 28 by pins 32 which are equally spaced in a circular series concentric with crankpin 22. The other connecting rods 33 of the other series are

45 articulated in the same way to spider 30 by pins 34. The crankshaft 20 is connected by any suitable means, such as that conventionally indicated at 36, to drive a shaft 35 at half speed.

Shaft 35 rotates in the same direction as shaft 20 and drives the breaker point mechanism

50 shown in Fig. 3.

In this diagram it may be assumed for the purpose of illustration that the firing position of the pistons is top dead center position. Cylinder 13 is in that position. The cylinder which

55 is in the same row as cylinder 13 and which is

next in firing order, is cylinder 9. Cylinders 9 and 13 are spaced 80 degrees. However, the piston of the cylinder 9 will not be exactly in firing position after an 80 degree movement of crank 22. This discrepancy results from the connection of the rod 31 to spider 28 rather than directly to the crank 22. For example, in Fig. 2, the crank 22 has been turned 80 degrees counterclockwise from its Fig. 1 position, but the piston 25 for cylinder 9 has not quite reached the top dead center position, as evidenced by the fact that the center line of rod 31 does not quite coincide with the radial center line 31 of cylinder 9. If one moves the crank 22 until the piston in cylinder 9 does reach top dead center position and measures the angle of crank movement, such angle will be found in this particular example to be 83 degrees.

One may determine for the entire group of 18 cylinders the angular movement between successive pairs of cylinders (taken in the order of their firing) necessary to bring the pistons into firing position. As a result, one would obtain a series of 18 angles each approximately 80 degrees but varying slightly therefrom. Having this series of angles, one may then lay out correctly the lobes on the cam which actuates the breaker point mechanism of the ignition means. The angles of the aforesaid series are divided by two to secure a series of angles representing the angles between successive lobes of the cam.

Due to the irregular spacing of the lobes of the cam, it has been thought necessary heretofore in order to secure accuracy of firing to use one large cam having as many lobes as there are cylinders (18 in this case) and to provide one breaker arm to ride on the cam. This means that the cam must be relatively large in diameter to accommodate so many lobes. If the cam is constructed as a polygon inscribed within a circle (like the cam shown in Fig. 4) the radial distance (such as x) between the high and low points of the cam will be very small and too small for the purpose. In Fig. 4 the nine lobe cam there shown is drawn twice its actual size. Therefore, the distances x are actually much less than shown. Consequently, with an 18 lobe cam the distances (corresponding to the distances x) would be much smaller and so small that it is necessary to recess the cam between the lobes by undercutting below a horizontal line which interconnects successive lobes. As a practical matter a cam, such as described, is very expensive to manufacture because the undercutting has to be done by grinding with exceedingly close accuracy.

The present invention is directed to the use of a single cam having half the number of lobes as there are cylinders and to the use of two breaker arms to cooperate with the one cam. Heretofore, such an arrangement has been considered impossible because of the described irregularity of firing positions and the compensatory irregular spacing of the lobes of the cam. However, I have worked out a certain angular spacing of these breaker arms relatively to the cam, which enables both arms to be correctly actuated at properly timed intervals to secure ignition in each cylinder at exactly the time when its piston reaches firing position.

Taking as a specific illustrative example, the engine shown in Fig. 1, and assuming that the firing order of the cylinders is 13, 2, 9, 16, 5, 12, 1, 8, 15, 4, 11, 18, 7, 14, 3, 10, 17 and 6, I determine the angular spacing of the lobes 40 of a

nine lobe cam in the following manner. Such cam will be suitable for one row of cylinders of the engine, say those having odd numbers. These cylinders fire in the following order—13, 9, 5, 1, 15, 11, 7, 3 and 17, and all fire during two revolutions of the crankshaft 20 and the respective angular movements of crankpin 22 necessary to bring the pistons 25 of these cylinders successively into firing position are in this particular case 83°, 79°, 74°, 83.5°, 81°, 83.5°, 74°, 79°, and 83°. These angles are halved and the resulting series is used, as shown in Fig. 4, as the spacing between the lobes 40. The arrow 42' represents a breaker arm in position to fire cylinder 13. The cam rotates counterclockwise and the numerals within the circles on the cam represent the various cylinders. If now one should work out in a similar way the angular spacing for the lobes of another cam suitable for use with the cylinders in the even numbered row, the second cam will be found to be identical with the first. However, if the cooperating breaker arm for this second cam were in the same location as arrow 42', the cam would have to be angularly offset from the first in order to function correctly. If, however, the two breaker arms are spaced apart by the amount of this offset (the second breaker is indicated by the arrow 43' in Fig. 4) the second cam could be turned until its contour exactly coincides with the first cam. Therefore, one cam can be used for both breaker arms providing these arms are correctly spaced, as shown in Fig. 4.

The spacing in this case is 140 degrees and it is determined by halving the angle of 280 degrees which is the angle through which the crankpin 23 of the even-numbered row of cylinders must travel in order to bring the piston 25 of its "master rod" cylinder 8 into firing position after the master rod cylinder 13 of the odd-numbered row has fired. Thus, in Fig. 1, cylinder 13 is shown in firing position and crankpin 23 must turn counterclockwise through an angle of 280 degrees before the piston in cylinder 8 moves into firing position. Since cam shaft 35 makes one revolution while the crankshaft makes two, the angle is halved to determine the spacing for the breaker arms.

In Fig. 3 the breaker point mechanism is shown, the breaker arms 42 and 43 (located like the arrows 42' and 43' in Fig. 4) have their leading or cam-contacting ends spaced 140 degrees. Each breaker arm is of insulating material pivoted at 45 to a plate 46 which is adjustably fixed in the usual way to a stationary support 47. Each arm carries a breaker point 48 to cooperate with a fixed breaker point 49 on plate 46. The right hand breaker point 49 is insulated from plate 46 as indicated. The arms are urged toward the cam 41 and the breaker points 48 and 49 urged toward closed position by a spring 50 which also serves as an electrical conductor to connect each point 48 to a terminal screw 51 mounted in a block 52 of insulation fixed to support 47. The usual condenser is indicated at 53. The breaker arms are operated in alternation to break the circuit through the primary coil 55 of any suitable ignition apparatus, such as a magneto or a battery-energized induction coil for example. The cooperating secondary coil, indicated at 56, is connected to the revolving arm 57 of a distributor which rotates counterclockwise at half engine speed and successively connects with the contacts shown. These contacts are numbered from 1' to 18' inclusive and are connected to the spark plugs of the respective cylinders bearing corresponding

but unprimed numerals. Thus, the contact 13' is connected by a wire 58 to the spark plug 59 of cylinder 13.

In operation, the breaker arm 42 has just been actuated by cam 41 to open the circuit to primary coil 55 and the distributor arm 57 is then engaged with contact 13', wherefore ignition occurs in cylinder 13, the piston of which is at that time in proper firing position (herein assumed to be top center position for convenience in illustration, but not necessarily such position). A succeeding 40 degree movement of crankshaft 20 turns cam 41 and arm 57 through an angle of 20 degrees, and in this position the primary circuit is broken by actuation of breaker arm 43 at a time when arm 57 connects with contact 2', thereby firing cylinder 2. Continued movement of the engine crankshaft will cause cam 41 to break the primary circuit and cause firing of the cylinders in the order shown in Figs. 4 and 5 which is the preestablished firing order first above described.

To secure a clear understanding of the invention, the factors of one particular engine have been given, such as the number of cylinders, number of rows of cylinders, spacing of the crankshafts, and spacing of the so-called master cylinders, and a particular spacing of cam lobes has been worked out to suit this engine. Obviously, all these factors may be varied and, if varied, a different spacing of cam lobes will result. Therefore, I do not intend to be limited by the various factors and dimensions herein stated, except insofar as they may be included in the appended claims.

What I claim is:

1. In a four-cycle internal combustion engine of the type wherein the cylinders are arranged in a plurality of rows with a plurality of cylinders in each row and the cylinders in each row radially disposed in a circular series about the axis of the crankshaft, and wherein the crankshaft has a plurality of cranks and master connecting rods one for each row, and one piston of one cylinder in each row is connected by said master rod to one of said cranks and the piston of the other cylinders in the same row are connected by rods articulated to the master rod for such row, a single cam driven from the crankshaft at half its speed and having a circular series of angularly spaced lobes equal in number to the number of cylinders in one said row, and a plurality of breaker point mechanisms one for each row of cylinders, each mechanism cooperating with the one cam but at angularly spaced locations relatively thereto, the angle between the cam-contacting parts of two successive mech-

anisms being equal to half the angle which the crank of one row must travel from its position at the time when the master piston of another row is in firing position to its position at the time when the master piston of the first-named row is in firing position.

2. In a four-cycle internal combustion engine, wherein the cylinders are arranged in two rows with a plurality of cylinders in each row and the cylinders in each row being radially disposed in a circular series about the axis of a crankshaft, having two cranks one for each said row, and wherein each crank is connected by a master connecting rod to the piston in one cylinder of its row and the pistons of the other cylinders of the same row are connected by rods articulated to the master rod of such row, a single cam driven at half the speed of the crankshaft and having a circular series of angularly spaced lobes equal in number to the number of cylinders in one row, two sets of breaker points one for each row and each set having a breaker arm to contact the cam and cause opening and closing of the points as the cam rotates, said breaker arms having their cam-contacting portions angularly spaced by an angle equal to half the angle which the crank for one row must move from its position at the time when the master piston of the other row is in firing position, to its position at the time when the master piston of its row is in firing position.

3. In a four-cycle internal combustion engine, wherein the cylinders are arranged in two rows with a plurality of cylinders in each row and the cylinders in each row being radially disposed in a circular series about the axis of a crankshaft, having two cranks one for each said row and spaced 180 degrees apart, and wherein each crank is connected by a master connecting rod to the piston in one cylinder of its row and the pistons of the other cylinders of the same row are connected by rods articulated to the master rod of such row, a single cam driven at half the speed of the crankshaft and having a circular series of angularly spaced lobes equal in number to the number of cylinders in one row, two sets of breaker points one for each row and each set having a breaker arm to contact the cam and cause opening and closing of the points as the cam rotates, said breaker arms having their cam-contacting portions angularly spaced by an angle equal to half the angle which the crank for one row must move from its position at the time when the master piston of the other row is in firing position, to its position at the time when the master piston of its row is in firing position.

KENNETH A. HARMON.
